UNITED STATES PATENT OFFICE.

CHARLES L. SLATTERY AND SEMION SAMBUR, OF CHICAGO, ILLINOIS.

DEVICE FOR LOCATING AND RAISING SUNKEN BOATS.

No. 851,698.

Specification of Letters Patent.

Patented April 30, 1907.

Application filed March 12, 1906. Serial No. 305,488.

To all whom it may concern:

Be it known that we, CHARLES L. SLATTERY and SEMION SAMBUR, citizens of the United States, and residents of Chicago, in the county of Cook and State of Illinois, have invented certain new and useful Improvements in Devices for Locating and Raising Sunken Boats, of which the following is a full, clear, and exact specification.

This invention relates to improvements in devices for locating and raising boats in which the device for locating the boat perform this function independently of devices for raising a boat and which consists respectively of a float and grappling device.

The prime object of this invention is to utilize the device for locating a sunken boat as a means for directing and guiding grappling devices and engaging the boat, and to have such device so constructed and coöperating as to render the engagement of the grappling device with a sunken boat absolutely certain, whether the boat be in an upright or tilted position, and by such means that the accidental disengagement of the grappling device from the boat is practically impossible.

A further object of our invention is to utilize the locating device for directing grappling devices to an engagement with a sunken boat at the best and predetermined point or points thereon, best adapted for raising a boat to the surface.

Another object is to have the grappling devices so constructed and arranged that they may be conveniently separated from the boat after being raised and secured and which is desirable in view of the enormous weight such grappling devices must necessarily have when employed to raise large vessels.

With these ends in view, our invention consists in certain features of novelty in the construction, combination and arrangement of parts, by which the said objects and certain other objects hereinafter appearing are attained, all as fully described with reference to the accompanying drawings, and more particularly pointed out in the claim.

In the said drawings: Figure 1, illustrates a sunken vessel and the means employed by which its location may be ascertained with absolute certainty. Fig. 2, a side elevation partly in section of grappling device embodying our invention but out of engagement with each other. Fig. 3, a side elevation of the

same showing the position of the grappling device on the cone when about to be lowered to engagement with the cone for raising a sunken vessel. Fig. 4, a detail view illustrating the adaptability of the locating devices for directing the grappling device to engagement with a vessel, the deck of which, as shown in section, is tilted and Fig. 5, a detail showing enlarged perforations for the rods connecting the gripping jaws and limiting the spread of said jaws.

Similar numerals of reference indicate the same parts in the several figures of the drawings.

6 indicates a vessel to the deck, 7, or suitable portions or timbers thereof, are secured a base-plate, 8, by means of bolts, 9, and mounted upon this base-plate and secured thereto by rivets, 10, or other suitable means are opposing brackets or lugs, 11-11, between which is hinged a yoke, 12, by means of a pivot, 13, between the arms of which yoke by means of a pivot, 14, is hinged a hook of peculiar construction, that is to say, 80 which consists of a stem, 15, by which the hook is directly hinged to the yoke and a cone shaped body, 16, provided at its base with an undercut, 17, forming adjacent the periphery of the cone a continuous hook, 18.

Cone, 16, is provided with a longitudinal perforation, 19, extending from the recess, 17, through the upper free and pointed end of the cone and paralleling the incline sides of the cone hook as shown in Fig. 2.

Passing upwardly through perforation, 19, and knotted or otherwise enlarged at its lower end to prevent its detachment by an upward pull, is a cable or rope, 20, which is of such a length that a float, 21, secured on the free end thereof will rise to the surface of any depth of water in which the boat may have sunk, and thereby indicate on the surface the location of such sunken boat, and for this purpose there may be one or more such devices secured to the deck of a boat or at any point below the deck but passing upwardly therethrough.

The hook structure just described is in practice secured to the boat at the best possible point for grappling the same in raising the boat to the surface, and for which purpose our invention includes a separate and distinct device adapted to coöperate therewith and which consists of two separate 111 movable jaws, 22--22, perforated at their upper ends, as indicated at 23, and strung, so to

speak, upon a ring, 24, from which they are loosely suspended so as to move inwardly and outwardly toward each other but which may be guided and limited in these movements by means of one or more, and preferably two bolts, 25, passing through larger perforations, 26, (see Fig. 5) in the body of the jaws, the clamping portions of which jaws are formed by right-angular bends, 27 10 and 28, therein, each of which is provided in its edge with a semi-circular cutout portion, 29, forming when the jaws are closed a circular opening for the reception of the point of the cone, whereby the jaws are thereby gradually spread apart until below the base of the cone when they will swing in toward each other beneath the base and in engagement therewith.

Ring, 24, has attached thereto a cable, 30, 20 of whatever length may be necessary to lower clamping jaws from the surface to the base of the cone on the sunken boat and the jaws together with the cone constitute a grappling device therefor as will now be explained.

The locating device which essentially consists of a rope secured to the cone in turn secured, as before described, to the vessel, and secured at its opposite end to a float which 30 together with the rope when not in use rests upon the deck of a vessel or may be in a receptacle of some kind on or below the deck provided with a cover which will automatically open and release the float as soon as the 35 boat sinks below the surface of the water, the rope being of such a length that the float will rest on the surface of the water at whatever depth the vessel may be.

With the boat thus located by the float, the 40 float with the rope is taken hold of and raised out of the water until practically in a vertical line when the rope, 20, is preferably passed through the ring, 24, as indicated in Fig. 3, and the jaws by their cable are then lowered to the cone hook, the rope, 20, of which thereby serves to guide the jaws thereto with such accuracy that if the rope, 20, is taut, as it should be to hold the cone in a vertical position, the jaws will pass over the 45 point of and down the cone until they swing inwardly engaged with and are firmly locked to the cone and in a position enabling the raising of the boat by pulling on the cable suspending the jaws. In this connection it 50 should be observed that the hinging of the cone so that, as before described, provides

for such a range of its movement that in whatever position the boat may rest, as for example, an inclined position such as is indicated in Fig. 4, the cone may be swung to a 60 vertical position, and in any event, to such an operative position as will enable the jaws to pass over the point of the cone and be locked to the base thereof, as before described.

As the grappling devices must necessarily be very strong and therefore correspondingly heavy, the rods, 25, limiting and directing the movement of the jaws to engage them with the cone are so constructed as to be removable, that is to say, are provided with nuts as indicated in Fig. 2 so that the jaws may be conveniently disengaged from the cone after the vessel is raised.

In practice there may be as many grappling cone hooks located as as many different points on the vessel at may be deemed advisable for the raising of the vessel and also there may be as many of the grappling jaw devices carried upon the wrecking or other 70 vessel as may be necessary to use in the raising of a sunken vessel.

The shank of the grappling hook might be connected with the deck of the vessel by a ball and socket joint, but in practice the 85 bolts of 13 and 14 are preferred for the reason that great strength of joint is necessary and which is better provided for by the bolts than is practical by ball and socket joint connection.

Having described our invention, what we claim and desire to secure by Letters Patent is:

In a device for the purpose described, a grappling hook means for securely hinging 95 said hook to the deck of a boat, a float, a rope connecting said float and hook and gripping jaws and a ring from which said jaws are loosely suspended, a cable secured to said ring and suspending said jaws, and bolts passing 100 through said jaws and limiting their movement away from each other, substantially as described.

In witness whereof, we have hereunto set our hands and affixed our seals, this 7th day 105 of March, 1906.

CHARLES L. SLATTERY.
SEMION SAMBUR.

In the presence of witnesses:

JNO. G. ELLIOTT,
ETHEL K. MANCHESTER.
